(Cl. D14—3)

Des. 180,871

PAGE 2

FIG. 3.

FIG. 4.

Fig. 1 is a side elevational view of an automobile showing my new design.

Fig. 2 is a front side perspective view of the same.

Fig. 3 is a front elevational view of the same.

Fig. 4 is a rear elevation of the same.

The essential features of my new design reside in the part shown in solid lines in the drawings.

I claim:

The ornamental design for an automobile, substantially as shown and described.
